UNITED STATES PATENT OFFICE.

CHARLES I. EARLL, OF NEW YORK, N. Y.

TROLLEY-RETRIEVER.

1,110,759.

Specification of Letters Patent. Patented Sept. 15, 1914.

Application filed June 17, 1909. Serial No. 502,744.

To all whom it may concern:

Be it known that I, CHARLES I. EARLL, a citizen of the United States of America, and resident of the city, county, and State of New York, have invented certain new and useful Improvements in Trolley-Retrievers, of which the following is a specification.

My invention relates to trolley retrievers.

The object of my invention is to provide a device of this character which shall be simple and effective in its construction and operation and one which shall be especially adapted for use on trolley cars of moderate speeds.

My invention consists in providing a drum for the trolley rope which is normally under the action of a relatively weak spring capable of rotating the drum to take up and pay out the slack which would otherwise occur in the trolley rope due to the variations in the height of the trolley wire or conductor, in providing a power spring which is normally wound up and locked, and means for automatically releasing the same when the trolley jumps the wire and causing the power spring to act upon the drum for one revolution or less of the drum, or for a limited number of revolutions, and in so arranging the mechanism that the drum may continue to revolve after the power spring has ceased to act upon it so as to take in the slack and retain the trolley pole in the lowest position to which it is brought by momentum.

In the retrievers heretofore in use it has been necessary in order to rewind or reset the power spring, to pull out an amount of rope equal to that which was taken in during the retrieving action, whereas by means of the novel mode of operation of my present invention the amount which the trolley is lowered by the retrieving action is considerably greater than the length of trolley rope which has to be withdrawn from the retriever to reset or rewind the power spring.

In the practical operation of my present invention, the retrieving action exceeds the length of rope required to be pulled out of the retriever by about fifty per cent.

My invention consists further in other novel features and constructions to be hereinafter more fully pointed out and described.

In the drawings accompanying and forming part of this application, Figure 1 is a partial section on line *a—a* of Fig. 2, Fig. 2

is a section on line *b—b* of Fig. 1, Fig. 3 is a partial section corresponding to Fig. 1 showing the parts in different relation, and Figs. 4, 5 and 6 represent respectively a partial side view, partial section and detail of a modification.

The reference characters are used in the same sense throughout the drawings and the specifications.

Numeral 1 represents the case which is formed of the shell 2 and the back 3. The back 3 has teeth 4 formed therein. The two parts 2 and 3 of the casing are held together by the central shaft 5 on the front end of which is secured the collar 6 while its back end is threaded and engaged by the thumb nut 7. Mounted on the shaft 5 is the intermediate 8. The intermediate has an elongated sleeve or hub 9 formed upon it which runs upon the shaft 5. The drum 10 is provided with a transverse web 11 which has a central opening bearing upon the sleeve 9 of the intermediate. The outer end of the drum is turned out so as to leave a shoulder 12 to receive the disk 13 which is made removable for the purpose of assembling and disassembling the power spring 14. The disk 13 has a central opening which bears upon the sleeve 9 of the intermediate. Between the disk 13 and the web 11, is the power spring 14, having its outer end secured to the drum and its inner end to the sleeve 9. In the recess in the end of the drum, on the other side of the disk 13, is the tension spring 15 which has its outer end secured to the drum and its inner end to the inwardly projecting hub 16 formed on the collar 6. The intermediate has a stud 17 formed upon it which carries the lock pawl 18. The lock pawl 18 has a tooth 19 which engages a tooth 20 on the drum and it has an end or abutment 21 which is adapted to engage the teeth 4 in the back. When the abutment 21 of the lock pawl 18 is out into full engagement with the teeth 4, the point of the tooth 19 will clear the tooth 20 on the drum; and similarly when the tooth 19 is in full engagement with the tooth 20 on the drum the lock pawl will clear the teeth 4. The lock pawl may, however, be partially withdrawn from its engagement with the teeth 4 so as to permit the tooth 20 on the drum to engage the tooth 19 on the lock pawl while the abutment 21 is still in engagement with the tooth 4, the purpose of which will be hereafter explained.

110

The centrifugal pawl 22 is pivotally mounted on the pawl 18. A spring 23 secured to the stud 24 of the centrifugal pawl 22 and bearing against the intermediate, tends to move the end of the centrifugal pawl toward the center of the drum, its inner position being determined by the engagement of the pin 26 with the web 25, formed on the intermediate. The web 25 is circular and concentric with the center of rotation of the intermediate, and the pin 26 rests upon the web 25 both when the lock pawl is in engagement with the drum as in Fig. 1 and when it is in engagement with the teeth 4 of the back as in Fig. 3, and the distance of the periphery of the web from the center is such as to bring the hook 30 of the centrifugal pawl in position to be engaged by the lug 31 on the drum. A radial rib or lug 27 is formed on the face of the drum and a radial lug 28 is formed on the face of the intermediate in the plane of the rib 27 so that the relative rotation of the drum and the intermediate in either direction is limited by the engagement of these two ribs or lugs. As shown in the drawings, the drum, if released, may make about seven-eighths of a revolution to the right, as seen in Fig. 1, before the lug 27 will engage on the opposite side of the lug 28 and cause the intermediate to rotate with the drum. The parts are shown in Figs. 1 and 2 in the position which they normally occupy when the power spring is wound up and locked and the trolley is on the wire. When there is a sudden jerk on the trolley rope, the centrifugal pawl is thrown outwardly against the action of the spring 23 and engages a tooth 4 in the back. The continued movement of the drum will then cause the lock pawl 18 to be forced out into engagement with a tooth 4. As soon as the tooth 19 has released the tooth 20 on the drum, the power spring will rotate the drum to the right, as seen in Fig. 1, winding up the trolley rope and pulling the pole down. The amount of this rotation under the action of the power spring is limited, as above stated, by the lugs 27 and 28 upon the drum and intermediate, respectively. The power spring 14 is preferably of such strength that after the lock pawl has been released and the drum has turned until the lug 27 has engaged the opposite side of the lug 28, it will still be strong enough to at least balance the upward pull of the trolley. During the turning of the drum, the drum and the trolley pole acquire momentum which, augmented somewhat by the tension spring 15 carries them beyond the point reached when contact is made between the lugs, and the drum and intermediate turn then together until the trolley comes to rest. At this point the lock pawl will engage the nearest tooth and maintain the trolley in this lowest position, since the spring 23 has a tendency to push

the lock pawl away from the drum into engagement with the teeth 4, as will be clearly perceived by considering the parts in the positions shown in Fig. 3. If the drum and intermediate were there turned slightly to the right so as to relieve the pressure between the end of the lock pawl and the tooth 4 which it engages and the lock pawl were pushed toward the drum, it is obvious that the stud 24 of the centrifugal pawl would turn relatively to the lock pawl and the spring 23 would be further wound around the stud and would resist such motion. It is therefore seen that by means of this construction the trolley may be lowered an amount greater than the amount of rope which will have to be withdrawn from the retriever in order to reset the power spring. The amount of this excess of retrieving action will of course depend upon the relative strength of the power spring and the trolley base springs, as well as the weight, friction etc. In practice I have found it to be from forty to fifty per cent.

When the centrifugal pawl 22 occupies a horizontal position above the center of the shaft, the centrifugal force must overcome the spring 23 and in addition thereto the effect of gravity on the centrifugal pawl, and when the centrifugal pawl occupies a horizontal position below the center of the shaft centrifugal force must overcome only the difference between the spring 23 and the effect of gravity on the centrifugal pawl. In order that the action of the centrifugal pawl may be uniform throughout its revolution, or in other words in order to neutralize the effect of gravity on the pawl, I make the points of contact between the centrifugal pawl and the teeth 4 eccentric to the center of the shaft 5 by making a cut 29 shown by dotted lines in Fig. 1, and full lines in Fig. 2. This eccentric cut in the teeth is made deep enough only to accommodate the centrifugal pawl 22. The abutment 21 of the lock pawl being broader makes contact with the teeth beyond the eccentric cut and is therefore not affected by said cut.

The centrifugal pawl 22 is provided with a lug 30 which engages the lug or point 31 on the drum. When the setting of the power spring is nearly completed, the lug 31 engages the hook 30 on the centrifugal pawl and pulls the lock pawl toward the drum until the point of the tooth 19 has come slightly within the radius of the tooth 20 on the drum at the same time as the lugs 27 and 28 come in contact. Then, when the pull on the trolley rope is relaxed, the drum, under the action of the power spring will turn to the right as seen in Fig. 1, and the engagement of the tooth 20 with the tooth 19 on the lock pawl will cause the pawl to pass into full engagement with the tooth 20 and out of engagement with the tooth 4 of the back.

To more clearly explain this action I will assume that, with the parts in the positions shown in Fig. 1 the lock pawl 18 has been thrown out of engagement with the tooth on the back, and that the centrifugal pawl has returned to its position where the pin 26 rests on the web 25, that is, the position in which the centrifugal pawl and the lock pawl are shown in Fig. 3. The drum and the lug 31, which is a part of the drum, will then turn to the right approximately seven-eighths of a revolution. The lug 31 will not then have passed the hook 30 on the centrifugal pawl. The lugs 27 and 28 prevent any further rotation of the intermediate and the drum under the action of the power spring. Then when the rope is pulled out from the retriever to wind up the power spring, the drum will turn to the left, and near the end of the turning, that is just before the lugs 27 and 28 come in contact, the lug 31 will engage the hook 30 and pull the lock pawl a short distance toward the drum, a distance sufficient, however, to bring the extreme point 19 of the lock pawl within the radius of the tooth 20 on the drum by the time that the lugs 27 and 28 have come in contact. Then when the pull on the trolley rope is relaxed the drum will turn slightly to the right under the action of the power spring, the lock pawl still being in engagement with the tooth of the back although it has been partially withdrawn from such engagement, until the tooth 20 engages the tooth 19. The angle of the contact surfaces is such that as the pull on the rope is further relaxed the lock pawl is forced home to its normal position shown in Fig. 1.

In Figs. 4, 5 and 6 I have illustrated a modification of my invention, by means of which the power spring is caused to act for more than one revolution, in fact for about one and three-quarters revolutions as shown. In this modification a disk 33 is interposed between the web 11 of the drum and the intermediate 8. This disk is provided with a lug 34 which engages the lug 27 on the drum, and a lug 35 which engages the lug 28 on the intermediate. The centrifugal pawl 36 is provided with a hook 37 which engages the lug 38 on the disk in lieu of the lug 31 on the drum in the former case. It will be obvious that in this modification when the lock pawl is released from the drum the drum will turn to the right as seen in Fig. 4 until the lug 27 engages the opposite side of the lug 34 on the disk and will continue to revolve, carrying the disk with it, until the lug 35 on the disk engages the opposite side of the lug 28 on the intermediate, after which the drum and intermediate will revolve together until the momentum is overcome by the trolley base springs.

Having thus described my invention what I claim is:

1. In a trolley retriever the combination with a drum, of a tension spring adapted to act upon said drum to cause it to take in the slack trolley rope, a power spring adapted to rotate the drum and normally wound up to a degree more than sufficient to overcome the upward pull of the trolley pole, means for automatically releasing said power spring on a sudden pull of the trolley rope whereby said spring is put into action and for limiting the amount of its action, including means for retaining the drum in the position to which it is carried by momentum after the power spring has ceased to act. 70

2. In a trolley retriever the combination with three relatively movable members, one constituting a drum, another stationary member and the third an intermediate, of a power spring having one end secured to said intermediate and the other end to one of the other of said members, a locking means between said intermediate and said member to which said power spring is secured adapted to retain said power spring in its normally wound up condition and a retaining means between said intermediate and said other member to retain said power spring after the release of said locking means and the unwinding of said power spring a predetermined amount, said locking means including means operating between said intermediate and the member not secured to said power spring permitting said drum to rotate in a direction to wind up trolley rope and opposing its rotation in a direction to unwind trolley rope when said retaining means is in action. 90

3. In a trolley retriever the combination with a drum adapted to receive the trolley rope, a power spring and mechanism by which said power spring is adapted to be automatically thrown into action on a sudden pull of the trolley rope to rotate the drum to wind up the trolley rope, of means for limiting the action of the power spring and causing it to cease to act before it has completely relaxed, and means governed by said mechanism for retaining the drum in the position to which it is carried by momentum after the power spring has ceased to act. 110

4. In a trolley retriever the combination with three relatively movable members, one constituting a drum for the trolley rope, another a normally stationary member and the third an intermediate member, said drum and said intermediate being concentrically and rotatably mounted, of a power spring connecting said intermediate member with one of the other of said members, 120 and a stop acting between said intermediate and the member connected with it by the power spring, adapted to limit their relative rotation in both directions and means acting between said intermediate and the said

member not connected to said power spring, permitting a forward and preventing a backward relative movement, whereby the drum will be caused to turn by momentum 5 and wind up and retain a certain amount of the trolley rope after the power spring has ceased to act upon it.

5. In a trolley retriever the combination with three relatively movable members, one 10 constituting a drum for the trolley rope, another a normally stationary member and the third an intermediate member, said drum and said intermediate being concentrically and rotatably mounted, of a power spring 15 connecting said intermediate member with one of the other of said members, and a stop acting between said intermediate and the member connected with it by the power spring, adapted to limit the unwinding of 20 said power spring and a ratchet and pawl connection between said intermediate and the said member not connected with the power spring permitting their relative rotation in one direction and preventing it in 25 the opposite direction, when the power spring has reached the limit of its unwinding.

6. In a trolley retriever the combination with a drum, of an intermediate mounted 30 concentrically with said drum and having a lug secured thereto a power spring connecting said drum and said intermediate tending 35 to rotate them in opposite directions and a lug on said drum adapted to engage said lug on said intermediate to limit their relative rotation in both directions.

7. In a trolley retriever the combination with a case provided with a tooth and a shaft mounted in said case, of a drum provided 40 with a tooth and an intermediate member rotatably mounted on said shaft, a power spring connecting said drum and said intermediate member, a lock pawl mounted on said intermediate member adapted to engage 45 the tooth on said drum and to be released therefrom and to engage the tooth on said case and to simultaneously engage the tooth on said drum and the tooth on said case.

50 8. In a trolley retriever the combination with a case provided with internal ratchet teeth and a shaft centrally located with respect to said teeth, of a drum and an intermediate rotatably mounted on said shaft, a power spring secured to said drum and to 55 said intermediate tending to rotate them in opposite directions, a tooth on said drum, and a lock on said intermediate adapted when in one position to engage the tooth 60 on said drum and clear the teeth in said case, in another position to engage a tooth in said case and clear the tooth on said drum, and in an intermediate position to simultane-

ously engage a tooth in said case and the tooth on said drum.

65 9. The combination with a drum of a centrifugal pawl pivotally mounted and adapted to revolve with said drum, a spring tending to hold the free end of said centrifugal pawl toward the center of revolution, and a plurality of teeth adapted to be engaged by said centrifugal pawl arranged eccentrically to the axis about which said centrifugal pawl revolves.

70 10. A trolley retriever case having a central opening for a shaft and provided with a plurality of teeth or abutments eccentric to said opening.

75 11. In a trolley retriever the combination with a drum, an intermediate and a power spring connecting said drum and intermediate, a casing in which said drum and intermediate are rotatably mounted provided with a plurality of teeth eccentric to the axis of said drum, a lock pawl pivoted to 80 said intermediate, and a centrifugal pawl pivoted to said lock pawl and adapted to engage said teeth.

85 12. In a trolley retriever the combination with a cage provided with a tooth, of a drum provided with a tooth rotatably mounted in said case, an intermediate mounted to rotate concentrically with said drum and connected therewith by a retrieving spring, a lock pawl mounted on said intermediate adapted to engage the tooth on 90 said drum and clear the tooth in said case, to engage the tooth in said case and clear said drum, and to simultaneously engage said teeth on said drum and said case.

95 13. In a trolley retriever the combination with a case provided with internal teeth and a shaft mounted in said case, of a drum provided with a tooth and a projection, and an intermediate member rotatably mounted on 100 said shaft, a retrieving spring connecting said drum and said intermediate member, a lock pawl pivotally mounted on said intermediate member and adapted to engage the teeth in said case in its outer position, the tooth on said drum in its inner position and to engage the teeth in said case and said drum in its intermediate position, and a centrifugal pawl pivotally mounted on said lock pawl adapted to engage the teeth in 105 said case to release said lock pawl from said drum and to engage said projection on said drum to draw said lock pawl into engagement with the tooth on said drum.

110 14. In testimony whereof, I have signed my 120 name to this specification in the presence of two subscribing witnesses.

CHARLES I. EARLL.
